UNITED STATES PATENT OFFICE.

WILLIAM H. BUELL, OF NEW HAVEN, CONNECTICUT, ASSIGNOR TO WINCHESTER REPEATING ARMS CO., OF NEW HAVEN, CONNECTICUT, A CORPORATION.

IMPACT-ILLUMINATED TARGET FOR PLEASURE-SHOOTING.

1,091,116.

Specification of Letters Patent. Patented Mar. 24, 1914.

Application filed October 11, 1913. Serial No. 794,592.

To all whom it may concern:

Be it known that I, WILLIAM H. BUELL, a citizen of the United States, residing at New Haven, in the county of New Haven 5 and State of Connecticut, have invented a new and useful Improvement in Impact-Illuminated Targets for Pleasure-Shooting; and I do hereby declare the following, when taken in connection with the accompanying drawings and the characters of reference marked thereon, to be a full, clear, and exact description of the same, and which said drawings constitute part of this application, and represent, in—

15 Figure 1 a view in front elevation of a target prepared in accordance with my invention. Fig. 2 a view thereof in vertical section on the line *a*—*b* of Fig. 1. Fig. 3 a view in elevation of a target, illustrating 20 its momentary illumination on the impact of an ordinary bullet.

25 My invention relates to an improvement in targets for pleasure-shooting, the object being to adapt a target to be momentarily illuminated about the point of the impact of a bullet by the action thereof, for the information of the user of the gun from which the bullet was fired.

With these ends in view, my invention 30 consists in a target having its impact-surface treated with a flash-light composition igniting on the impact of the bullet to produce a circumscribed illumination of the target about the point of the impact of the bullet upon its surface.

In carrying out my invention, I employ 35 a target 2 which may be made of iron or any other material suitable for the purpose. As these targets are used for pleasure-shooting, they may be made on a large or on a small scale. If desired, they may be given 40 a pictorial character, simulating hunting or other scenes. The square target illustrated in the drawings is, then, merely illustrative 45 and not definitive. The outer or impact-surface of the target is prepared with a thin, superficial coating 3 of any one of a great variety of flash-light compositions adapted in character to be momentarily ignited in a

circumscribed area on the impact of a bullet. 50 As an example of such a preparation, I may instance a composition of chlorate of potash, magnesium and collodion applied by an ordinary brush. I wish it understood, however, that I do not limit myself to the employment of any particular flash-light composition. When a bullet hits the prepared surface of my improved target, the composition is immediately ignited at the point of impact with the production of a momentary 55 flash of light, whereby a circumscribed area around the point of impact is illuminated, giving the person holding the gun from which the bullet was fired information as to the exact point upon the target, hit. 60 I should say, further, that the character of the composition is such that the ignition does not spread over the entire surface, but confines itself closely to the portion of the surface actually hit by the bullet. It will 65 be desirable to recoat the target from time to time with the composition, since any point on its surface that has once been ignited will not be ignited on being hit a second time, unless recoated in the interval. By 70 recoating the target, it can be used indefinitely. In Fig. 3 of the drawings, the action 75 of the bullet upon the surface of the target is illustrated by four illuminated areas 4.

80 I claim:—

As a new article of manufacture, an impact-illuminated target for pleasure-shooting, having its impact surface prepared with a flash-light composition ignited by the impact of a bullet at the point of the impact 85 thereof with the said surface, whereby a circumscribed area about the point of impact is illuminated and the user of the gun from which the bullet was fired informed of the point hit. 90

In testimony whereof, I have signed this specification in the presence of two subscribing witnesses.

WILLIAM H. BUELL.
